7 Claims

in each C_nH_{2n} group, n is conveniently 2 or 3 and x is
preferably from 1 to 3. The most preferred alcohol is
monobutyl diethylene glycol.The invention is particularly applicable to the preparation
5 of acetals of heliotropin. It is preferred, according to
our invention to react an alkyl ether alcohol of the formula
 $RO(C_nH_{2n}O)_xH$ (wherein n in each $C_nH_{2n}O$ group
is 2 or 3, x is an integer from 1 to 3 and R is an alkyl
group having from 1 to 6 carbon atoms) with heliotropin
at a temperature of from 140 to 180° C. in a substantially
non-polar refluxing medium, and to separate the water
from the system.Preferably the alkyl ether alcohol has the aforesaid formula
15 wherein n is 2, x is conveniently 2 or 3 and R may
be for example n-butyl, propyl or ethyl.We have discovered that, when a single batch of alkyl
ether alcohol (for example monobutyl diethylene glycol)
20 and heliotropin are refluxed at 120 to 200° C. in a sub-
stantially non-polar medium, yields approaching, but
seldom exceeding, 50% may be achieved. However, the
unreacted starting materials are largely recoverable and
may be reused, giving yields which may approach 80%
for continuous, or repeated batch operations.Our invention according to its preferred embodiment
25 therefore provides a method of preparing a pyrethrum
synergist, which comprises refluxing heliotropin with an
alkyl ether alcohol in a substantially non-polar medium
30 consisting substantially of a petroleum fraction, the mixture
having a boiling point between 120 and 200° C. separating
the water evolved from the system, recovering
unreacted starting materials for reuse, and recovering an
acetal of heliotropin as product.Surprisingly the presence of small quantities of acids or
35 salts, such as are conventionally used to catalyse the
formation of acetals, appears to have no beneficial effect
in the method of our invention and generally results in
reduced yields of acetal. Although traces of certain con-
ventional acetal forming catalysts can be tolerated with-
40 out serious loss, the yield of acetal generally declines
drastically if quantities of such catalysts in excess of few
percent by weight are present. In general therefore we
prefer to carry out the reaction in a substantially non-
polar solvent in the substantial absence of added polar
substances.45 The nature of the solvent system is critical. If solvent
more polar than an aliphatic hydrocarbon oil such as a
petroleum fraction are employed the yield is greatly re-
duced. Thus even in solvents of fairly low polarity such
as xylene or toluene, it may be difficult or impossible to
50 obtain economic yields of the product. Also critical is the
reaction temperature which is commonly determined by
the reflux temperature of the solution. We have found
that the reaction is too slow to give a useful yield at temper-
55 atures of 120° C. or below and tends to give a highly
impure product at temperatures above 200° C. The pre-
ferred temperature range is 140° C. to 180° C. The pre-
ferred solvent is a petroleum fraction boiling within this
range e.g. at 140 to 160° C. petroleum fraction.60 Water may be separated from this system by cohabitation. Surprisingly it has been found that a quantity of
water approaching the stoichiometric amount for a complete
reaction may sometimes be evolved, even when the
yield of product is less than 50%. The majority of the
water is evolved during the first hour although evolution
continues at a reduced rate for up to seventeen hours. In
65 general the highest yields of product are obtained after
seventeen hours, although the reaction may be stopped
sooner to obtain slightly lower yields of a purer product.In general it is convenient to employ an excess of alcohol
70 over the stoichiometric proportion of two moles of alcohol
to one of aldehyde e.g. a 100% excess, but these proportions
are not critical and may be varied within wide

ABSTRACT OF THE DISCLOSURE

Acetals, and particularly acetals useful as synergists for pyrethrum are prepared by a reaction of an aromatic aldehyde such as 3,4 methylenedioxybenzaldehyde with alkyl ether alcohols in a substantial non-polar medium refluxing at a temperature between 120 and 200° C. and consisting essentially of a hydro saturated hydrocarbon solvent.

The present invention relates to the preparation of acetals and in particular to the reaction of alkyl ether alcohols with aromatic aldehydes. The invention is of particular value for the preparation of pyrethrum synergists.

The preparation of acetals is usually achieved by the reaction of two moles of an alcohol with one mole of an aldehyde in the presence of an acid catalyst, and removal of water from the system, for example by refluxing with a suitable non-aqueous solvent. It has been discovered, however, that in a few instances the yields obtained from this reaction are too low for it to be commercially feasible, and the product is heavily contaminated with impurities. A particular example which is of commercial importance is the preparation of alkyl ether acetals of 3,4 methylenedioxybenzaldehyde (also referred to as heliotropin) e.g. the acetal derived from the monobutyl ether of diethylene glycol. These acetals are valuable ingredients of insecticidal compositions, and particularly compositions containing pyrethrum, with which the acetal has been found to exert a synergistic insecticidal activity (see for example British Patent 1,085,645). The direct catalysed reaction of alkylether alcohols with heliotropin gives such poor yields that it has been proposed in British Patent 1,085,645 to make the acetal commercially by a cumbersome and expensive two stage reaction, which comprises converting the aldehyde to a dichloride which is reacted with the sodium salts of the alcohol.

We have now discovered that aldehyde such as heliotropin may be reacted directly with alkyl ether alcohols to form acceptable yields of acetal, provided the reaction is effected at 120 to 200° C. in a substantially non-polar medium.

As used herein "a substantially non polar medium" is a solvent system having a polarity no greater than that of a saturated aliphatic hydrocarbon, and containing no more than trace quantities of acids, bases or salts, as illustrated in the examples.

Our invention therefore provides a method of preparing acetals which comprises reacting an aromatic aldehyde with an alkyl ether alcohol at a temperature between 120 and 200° C. in a substantially non-polar medium as herein defined, and removing the water evolved from the system.

Preferably, the reaction is effected at substantially atmospheric pressure by refluxing the reactants in a petroleum fraction at a refluxing temperature of between 120 and 200° C., and preferably from 140 to 180° C.

Preferably the alkyl ether alcohol has the formula $RO(C_nH_{2n}O)_xH$ where R is an alkyl group and n and x are integers. R preferably has from 1 to 6 carbon atoms

limits. For example 4 to 5 times the stoichiometric amount of alcohol may be employed.

It is convenient to reflux the alcohol in the paraffin solvent to drive off any water, and to add the aldehyde. The mixture may then be refluxed until no further evolution of water occurs. Preferably the unreacted alcohol and aldehyde are recovered by distillation under reduced pressure. To isolate the product, distillation under still lower pressures may conveniently be employed.

The invention will be illustrated by the following examples, illustrating the preparation of the acetal,

EXAMPLE 1

81 g. of monobutyl diethylene glycol and 250 mls. of a paraffin oil having a boiling point of 140 to 160° C. sold under the name Shell Special Boiling Point Spirit No. 6 (hereinafter referred to as SBP 6) were gently refluxed with stirring for 0.75 hour during which period 0.5 ml. water was collected in a Dean and Stark trap. 38 g. heliotropin was added to the hot solution and the mixture refluxed at a temperature of 158 to 160° C. for 17 hours. 4.5 mls. of water collected. The solution was allowed to cool to 30° C. and the solvent was recovered by distillation under reduced pressure of 3 to 7 mm. Distillation of the residue under reduced pressure yielded:

- (a) 35 g. monobutyl diethylene glycol and heliotropin
- (b) 12 g. monobutyl diethylene glycol, heliotropin and acetal
- (c) acetal (B.P. 200 to 230° C. at 0.04 mm. yield 48.7% n_D^{18} 1.4838)
- (d) 6.5 high boiling residue.

EXAMPLE 2

Monobutyl diethylene glycol (81 g.) and SBP 6 (100 ml.) were gently refluxed with stirring for 1.25 hours during which period water (0.7 ml.) was collected in a Dean and Stark trap. The solution was allowed to cool to 90° C. over 0.75 hour and heliotropin (38 g.) added. The solution was refluxed for 39 hours (thrice interrupted overnight) during which period water (4.6 ml.) was collected in the Dean and Stark trap. (The temperature of the solution varied between 168 to 73°).

The resulting red solution was allowed to cool and the SBP 6 distilled under 7 to 8 mms. pressure. The residue was distilled to yield 47 g. acetal B.P. 200-30°/0.02 mm. n_D^{18} , 1.4849. Yield was 41%.

EXAMPLE 3

(i) Monobutyl diethylene glycol (162 g.) and SBP 6 (500 ml.) were refluxed with stirring for 0.75 hour during which period water (0.7 ml.) was collected in a Dean and Stark trap. The solution was allowed to cool to 100° over 0.75 hour and heliotropin (76 g.) added. The solution was refluxed for 28 hours (twice interrupted overnight) during which period water (7.6 ml.) was collected in the Dean and Stark trap.

The resulting golden-red clear solution was allowed to cool and SBP 6 distilled under 3 to 5 mms. pressure. The residue was distilled to yield products—

- (a) 109.5 g.—monobutyl diethylene glycol and heliotropin B.P. <200°/0.01 mm.
- (b) 102 g.—acetal, n_D^{20} , 1.4842, B.P. 200°/0.02 mm. 250°/0.08 mm.
- (c) 9.5 g.—high boiling products.
- (d) 38.5—mostly monobutyl diethylene glycol and heliotropin B.P. 200°/0.01 mm.
- (e) 57 g.—acetal $n_D^{20.5}$, 1.4845, B.P. <200°-240°/0.02 mm.
- (f) 5.5 g.—high boiling products.
- (g) 15 g.—mostly monobutyl diethylene glycol and heliotropin B.P. <200°/0.005 mm.
- (h) 15.5 g.—acetal, n_D^{23} , 1.4840, B.P. 200-30°/0.01 mm.
- (i) 2 g.—high boiling products.

The resulting clear red solution was worked up as above to yield products—

- (j) 36.5 g.—mostly monobutyl diethylene glycol and heliotropin B.P. 200°/0.01 mm. (0.9 ml.). Products worked up as above were—
- (k) 15 g.—mostly monobutyl diethylene glycol and heliotropin B.P. <200°/0.005 mm.
- (l) 15.5 g.—acetal, n_D^{23} , 1.4840, B.P. 200-30°/0.01 mm.
- (m) 2 g.—high boiling products.

The yields of tropital, w.r.t. starting products for each stage were—

	Percent
(i)	44.5
(ii)	54.3
(iii)	44.1

This gives an overall yield of acetal for the three stages of 76.2%.

EXAMPLE 4

Parts (i) and (ii) of Example 3 were repeated using White Spirit (B.P. 150-200° C.) as solvent in place of SBP 6. Yields of acetal were—

	Percent
(i)	40.6
(ii)	41.2

giving an overall yield of 60%.

EXAMPLE 5

Monobutyl diethylene glycol (162 gms., equivalent to 100% excess), SBP 6 (250 mls.) and heliotropin (38 gms.) were mixed, brought to the boil in 12 minutes and gently refluxed for 1½ hours, during which time 0.2 c.c.s. water was collected by way of a Dean and Stark trap.

The solution was allowed to cool to 80° C. and then again brought to the boil in 7 minutes and refluxing continued for a total period of 20 hours, collecting the water of reaction in the Dean and Stark trap.

The solution was allowed to cool overnight and then partly distilled under reduced pressure to remove the petroleum solvent. The residue was distilled at 1 mm. collecting some recovered heliotropine and glycol, together with tropital fractions B.P. 230-250/1 mm.

- (a) 13.5 gms., assay 86%
- (b) 62 gms., assay 100.4%

Yield 59% theory.

We claim:

1. A method for the manufacture of an acetal which comprises heating 3,4-methylenedioxybenzaldehyde and an alkyl ether alcohol of the formula $RO(C_nH_{2n}O)_xH$, wherein n is an integer from 2 to 3, x is an integer from 1 to 3, and R is an alkyl group having from 1 to 6 carbon atoms, under reflux in a substantially non-polar medium consisting essentially of a saturated hydrocarbon solvent having a boiling point between 120 and 200° C.
2. The method according to claim 1 wherein the reaction mixture refluxes at a temperature of 140 to 180° C.
3. The method according to claim 1 wherein the solvent is a petroleum fraction having a boiling point of 140 to 160° C.
4. The method according to claim 1 wherein the alcohol is the monobutyl ether of diethylene glycol.
5. The method according to claim 1 which comprises heating 3,4-methylenedioxybenzaldehyde with said alkyl ether alcohol at reflux temperature in a substantially non-polar medium consisting essentially of a saturated hydro-

carbon solvent boiling at a temperature of from 140 to 180° C., separating water from the system by cohabitation, recovering unreacted starting materials for re-use and recovering an acetal product.

- 5 6. The method according to claim 5 wherein the alkyl ether alcohol is employed in stoichiometric excess of up to 500%.

7. The method according to claim 6 wherein the alcohol is the monobutyl ether of diethylene glycol.
